United States Patent Office

Des. 182,495
Patented Apr. 15, 1958

182,495

WALL PAPER

Kirtley E. Black, White Plains, N. Y., assignor to Black, Starr & Gorham, Inc., New York, N. Y., a corporation of Delaware

Application April 11, 1957, Serial No. 45,683

Term of patent 14 years

(Cl. D59—10)

The figure illustrates a section of wall paper embodying the new design and in which the area enclosed by the dot and dash lines constitutes one full repeat which is repeated throughout the width and length of the wall paper.

I claim:

The ornamental design for a wall paper, as shown and described.
